UNITED STATES PATENT OFFICE.

EDWARD W. McCANNA, OF ANACONDA, MONTANA.

STEAM-BOILER.

SPECIFICATION forming part of Letters Patent No. 705,779, dated July 29, 1902.

Application filed March 22, 1902. Serial No. 99,523. (No model.)

To all whom it may concern:

Be it known that I, EDWARD W. McCANNA, a citizen of the United States, residing at Anaconda, in the county of Deerlodge and State of Montana, have invented a certain new and useful Improvement in Steam-Boilers, of which the following is a full, clear, and exact description.

A main object of this invention is to provide a tubular steam-boiler composed largely or wholly of commercial shapes and that may be readily transported and set up in mountainous regions with little or no regular boiler-shop work.

15 In carrying out my invention I prefer to use top and bottom headers of serpentine form, each composed of sections of steel tubing united by return-bends of cast-steel, to which they are calked and riveted, the headers being connected to each other by regular 20 rolled-steel boiler-tubes expanded in any ordinary way into the headers, and a steam-drum connected with the top header by steel nozzles. The bends are provided with hand-hole plates, and the ends of the headers are provided with manhole-plates. I prefer also to use a setting having a downdraft, so that the products of combustion will pass between the headers and about their connecting-tubes 25 and then out beneath the bottom header, all as I will proceed now more particularly to set forth and finally claim.

In the accompanying drawings, illustrating my invention, in the several figures of which 35 like parts are similarly designated, Figure 1 is a side elevation and partial section of the boiler arranged in a downdraft-setting, which is shown in vertical longitudinal section.

Fig. 2 is vertical cross-section taken substantially in the plane of line A B, Fig. 1. Fig. 3 is a plan view illustrating the lower header.

The top and bottom headers are of like construction, excepting as hereinafter specified, and so far as they are alike a description of one will suffice for both. The pipes *a* may be of rolled steel or other commercial form and any size, and they are connected in serpentine form by cast-steel return-bends *b*, said pipes and return-bends being united by 45 calking and riveting. The bends are supplied with hand-hole plates *c* and the ends with manhole-plates *c'* of approved construc-

tion. The bottom header is provided with the water-intake *d*, also of approved construction. The top and bottom headers are 55 set staggering, and hence their connecting-tubes *e* are inclined forwardly, as shown in Fig. 1, in order the better to utilize the products of combustion. These tubes *e* are preferably commercial rolled-steel boiler-tubes, arranged in pairs and expanded into the header-tubes *a* in any ordinary manner. The steam-drum *f* is mounted above the top header and connected therewith by steel nozzles *g*. Said drum is provided with a cast-steel elbow *f'* 60 at one end, which may receive the safety-valve, and the other end may have a crown-valve *f''* applied to it. Flange-joints may be used for connecting these parts, substantially as shown.

The boiler is set in masonry, having a grate *h* and a horizontal partition *i*, in which the bottom header is embedded and which is about on a level with the grate, while the top header is in the upper wall of the setting. The rear 75 wall *j* of the setting extends beyond the boiler and forms a chamber *k*, communicating with or constituting a part of the combustion-chamber *l* and opening into the outlet-flue *m* beneath the bottom header, which flue in 80 turn opens into the smoke-conduit *n*, leading to the chimney or stack, so that the products of combustion circulate beneath the top header, above the bottom header, around the tubes *e*, and thence beneath the bottom header 85 to the escape.

Since the blow-outs, valves, gages, and other adjuncts of a boiler are not of the novel features of the invention, I omit them from this specification.

The feed-water is introduced into the bottom header and circulates freely up and down the tubes, connecting the top and bottom headers, and from front to rear in the top and from rear to front in the bottom header. 95

As already stated, the tubes are to be the regular rolled-steel boiler-tubes and expanded into the headers in the usual way of inserting tubes in tubular boilers. Cast-steel return bends are used because of their strength 100 and the ease and low cost with which they can be made. The boiler thus can be built very cheaply and without any of the regular boiler-shop work by manufacturers of steel

tubing, and all its members being comparatively small and light they can be transported easily through mountainous regions and assembled in the field.

5. While I prefer to use the downdraft, I do not limit my invention thereto.

What I claim is—

1. A steam-boiler header, of serpentine form, composed of pipes and cast-steel return-bends united by calking and riveting.

2. A steam-boiler, composed of top and bottom headers of serpentine form, constructed of commercial pipes and cast-steel return-bends calked and riveted to said pipes, and 15 steel upright tubes expanded into said pipes, substantially as described.

3. A steam-boiler, composed of top and bottom headers of serpentine form, constructed of commercial pipes and cast-steel return-bends calked and riveted to said pipes; and 20 steel upright tubes expanded into said pipes, combined with a steam-drum and steel noz-

zles connecting it with the pipes of the top header.

4. A steam-boiler, composed of top and bottom headers of serpentine form, constructed of commercial pipes and cast-steel return-bends calked and riveted to said pipes, and 25 steel upright tubes expanded into said pipes, combined with a setting having a downdraft 30 including a horizontal partition in which the bottom header is arranged.

5. In a steam-boiler, a serpentine header composed of pipes with cast-steel return-bends having hand-hole plates, and manhole-35 plates at the ends of the header, substantially as described.

In testimony whereof I have hereunto set my hand this 15th day of March, A. D. 1902.

EDWARD W. McCANNA.
